CAMBERING MECHANISM FOR GRINDING MACHINES

Clifford L. Schulte, Rossmoyne, and Andrew J. Graf, Norwood, Ohio, assignors to Cincinnati Grinders Incorporated, Cincinnati, Ohio, a corporation of Ohio

Application November 7, 1938, Serial No. 239,294

11 Claims. (Cl. 51—33)

This invention relates to grinding machines and more particularly to the type of machine utilized for producing cambered surfaces on work.

One of the objects of this invention is to produce a camber grinding machine which has a sufficiently large range of adjustment to encompass all commercial cambers now being produced.

Another object of this invention is to provide a cambering mechanism for a grinding machine which is rugged in construction and which, although adjustable, has all of the adjustable parts positively connected and positively driven.

A further object of this invention is to provide a cambering mechanism which is simple in construction, which may be positively set, and which may be reset in exactly the same condition to reproduce a given camber.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the invention.

Referring to the drawings in which like reference numerals indicate like or similar parts:

Figure 1 is a cross sectional view through a grinding machine embodying the principles of this invention.

Figure 2 is an enlarged view of the camber control mechanism as viewed on the line 2—2 of Figure 1.

Figure 3 is an expanded view of the cambering mechanism showing the drive arrangement as viewed on the line 3—3 of Figure 2.

Figure 4 is a plan view showing camber control parts locked together for driving.

Figure 5 is a view similar to Figure 4 with the parts unlocked and in position for adjustment.

Figure 6 is a section on the line 6—6 of Figure 4.

Figure 7 is a diagrammatic view showing the relative relation between the grinding wheel and work during adjustment of the cambering mechanism.

Figure 8 is a detail view showing the table driving mechanism.

Figures 9, 10 and 11 are diagrammatic views to illustrate the method of adjustment in setting up for a given camber.

Referring to Figure 1 of the drawings, the reference numeral 10 indicates generally the bed of a grinding machine upon the top of which are formed guideways 11 and 12 for receiving a traversing work support or table 13. This table has the usual head and tailstock means for rotatably supporting a work piece, which is indicated in the

drawings by the reference numeral 14. The work is rotated relative to the rotatable grinding wheel 15, and is also adapted to be traversed axially relative to the wheel when it is longer than the face of the grinding wheel is wide. This traversing movement may be effected by power means, such as that shown in Figure 8, and consisting of a power operated motor 16 which rotates a worm 17 through drive shaft 18. The worm intermeshes with a worm gear 19 secured to the end of shaft 20 which also has pinion 21 intermeshing with a rack 22 secured to the underside of the table.

For producing cambered work, such as rolls for steel mills and the like, it is necessary to produce a second relative movement between the grinding wheel and the work and in a direction at right angles to the direction of traverse so that the diameter of the work may be gradually increased or decreased in a uniform manner during traverse. By proper control of this movement, various cambers of either a convex or concave variety may be produced.

The mechanism for producing the cambering movement of the wheel is positively driven in timed relation with the traverse of the table and is adjustable to produce any commercial camber now in use. The mechanism for setting and locking the adjustable parts for a given camber is so accurate that it may be reset in exactly the same position to reproduce a given camber.

The cambering mechanism receives its power from the moving table so as to be in timed relation therewith, and as shown, the table rack 22 rotates a pinion 23 and its supporting shaft 24, the latter being journaled in the bed. This shaft carries a bevel pinion 25 for transmitting rotation to a bevel gear 26 secured to a sleeve 27. The sleeve is supported for rotation in the bed and has a splined bore 28 by which it is operatively connected to the splined end 29 for rotation of shaft 30. The shaft 30 extends to the rear of the machine where it is provided with a pinion 31 for rotating a pair of change gears 32 and 33 through pinion 34 and shaft 35. The gear 33 is keyed to the end of shaft 36 which has a gear 37 keyed to the other end and meshing with spur gear 38. It will be noted that the gears 34, 32 and 37 are all positively keyed to their respective shafts.

The gear 38 is supported for axial movement relative to a supporting sleeve 39. When the gear 38 is in driving position, internal teeth 40 on the gear intermesh with external teeth 41 formed on the end of the sleeve 39 and this forms a positive driving connection between the gear 38 and the sleeve 39. The gear 38 is capable of sufficient axial movement to disengage teeth 40 from teeth 41 while remaining in mesh with the gear 37. When this driving connection is broken the sleeve 39 is free to be rotatably ad-

justed while the gear 38 is held against rotation by the gear 37. The sleeve 39 is anti-frictionally supported for rotation on a fixed stud 42 and the teeth 41 are concentric with respect to the axis of the stud. The sleeve, however, has an eccentric portion 43 upon which is supported a cam member 44 having a cam track 45 which is eccentric with respect to the axis of its bore 46. The eccentricity of the periphery of the sleeve with respect to the axis of the stud 42 is equal to the eccentricity of the periphery of the cam track with respect to its bore, whereby if these two parts are relatively adjusted so that the eccentricities are opposite to one another, the center of the cam track 45 will lie in the axis of the stud 42 and no resultant eccentricity, so far as the cam track is concerned, will be present. With the parts in this position the eccentricity may be said to be zero.

The grinding wheel 15 is supported for rotation on a longitudinally movable slide 47 which also carries the prime mover, such as 48, for rotating the grinding wheel. The slide 47 may be traversed by any conventional form of mechanism, but since this mechanism forms no part of the present invention the same is not illustrated herein. The slide 47 is guided on a support 49 which is adapted to be oscillated relative to the bed 10 to effect movement of the grinding wheel in a substantially radial direction with respect to the work. To this end a pivoted connection 50 is provided and it will be noted that the axis of this pivot is directly below the grinding wheel. The free end of support 49 rests on a plunger 51 which has a roller 52 riding on a lever 53 as shown in Figure 2. The lever 53 is fulcrumed at 54 in the bed of the machine and the free end of the lever is provided with a follower roller 55 which engages the periphery of the cam track 45. It should now be apparent that if the axis of rotation of the cam is concentric with the axis of the stud 42, no oscillation of the lever 53 will take place, and therefore, a true cylindrical surface will be produced on the work.

It is common practice in setting up for a given camber to first position the table longitudinally to place the longitudinal center of the work opposite the center of the grinding wheel face. In other words, the parts will be in the position diagrammatically indicated in Figure 7. The cambering mechanism is then adjusted to the desired setting. It will, therefore, be assumed that the work and grinding wheel are in the relative positions indicated in Figure 7 while making the following adjustments.

Referring to Figures 9, 10 and 11, the cam track 45 and the eccentric sleeve portion 43 are illustrated diagrammatically to show the relationship of the eccentrics. The reference numeral 56 indicates the center of the fixed stud 42 which is also the center of rotation of the parts during operation of the machine. The periphery of the eccentric sleeve portion 43 is a true circle and its geometrical center is indicated by the numeral 57. In the position of zero camber the center 57 lies on axis 59-59 which is perpendicular to the axis 59-59 passing through the center of rotation 56 and the center of the follower roller 55.

The periphery of the cam track 45 is also a true circle, the geometric center 60 of which is superimposed on the center 56 in the zero camber position indicated in Figure 9. Therefore, since the geometrical center of the cam track lies in the center of rotation it is apparent that

the parts can be jointly rotated without effecting movement of the grinding wheel either toward or from the work.

As shown in Figures 4 and 5, the cam member 44 and the sleeve 39 are provided with zero graduation marks 61 and 62 respectively. When the parts are in the position shown in Figure 9, the zero marks 61 and 62 are in alignment with a third zero mark 63 formed on the periphery of a plate 64 permanently attached to the end of the stud 42. This plate serves to retain the sleeve on the stud. Thus, when all three zero graduation marks are aligned, it automatically places the parts in zero camber position.

It will be evident that in initially moving the grinding wheel toward or away from the work that the center of the cam track 45 must when shifted remain on the axis 59-59 if the maximum or minimum setting is to be obtained, the direction of shifting depending upon whether the camber is to be concave or convex. It will be evident that with the center 60 above or below the center of rotation 56 that the cam track will produce the same effect as regards the amount and direction of movement of the grinding wheel with respect to the work regardless of its direction of rotation.

The shifting of the center of the cam track above or below center is accomplished in part by rotating the sleeve 39 and in so doing the axis 58-58 will rotate about the center 56 into some assumed position, such as that shown in Figure 10. Assuming the cam held against rotation, the axis 65-65 which connected the centers 57 and 60 will move laterally downward to the position shown in Figure 10 and since the geometrical center of the cam track lies on this axis and is a fixed distance from the center 57, the center 60 must have shifted not only downward but to the right of axis 59-59.

It is necessary, however, as stated supra, that the center 60 lie on the axis 59. This may be accomplished by rotating the axis 65 about the center 57 through an angle equal to the angle through which the axis 58 was rotated about the center 56.

When this is done the parts will be in the position shown in Figure 11 and the angle 66 will be equal to the angle 67. This will reposition the center 60 of the cam track on the axis 59, but a desired amount above or below center to produce the desired camber at the center of the work. It will be noted that the axis 58 was rotated in a counterclockwise direction while the axis 65 was rotated in a clockwise direction. That is the reason why the graduations on the sleeve and cam extend in opposite directions from the respective zero points in Figures 4 and 5. The individual rhombs of the scale may be numbered consecutively, and a separate chart provided to show the amount of camber for different position combinations. It will be evident that the angle of rotation of the cam and sleeve must be equal and opposite in order to have the center of the cam track lie on the perpendicular axis passing through the center of a follower roller so that the rate of increase or decrease in the camber will be the same for either direction of rotation of the cam track. Therefore, the sleeve and cam are rotated until the same graduation numbers are aligned with the zero mark 63 on the plate 64. It is then only necessary to shift the cam member 44 axially to effect engagement of teeth 40 and 41. The cam member must now be secured to the sleeve for rotation therewith and

this is accomplished by providing a series of equally spaced radial graduation holes 68 in the sleeve 39 and all lying in a single plane. In addition, the cam member is provided with a series of equally spaced radial vernier holes 69, but spaced closer than the holes in the sleeve.

These holes are so spaced that for each setting only one pair of holes will be in alignment. A locking pin 70 is inserted in the aligned holes and if the holes are slightly out of alignment, the insertion of the pin will automatically correct the alignment. This makes it possible to repeat a setting with absolute accuracy and without depending upon the ability of a workman to align exactly two graduation marks. The pin also serves as a positive driving connection between the sleeve and the cam member.

The locking pin has an annular groove 71 formed therein for engagement with a spring pressed detent 72, as more particularly shown in Figure 3. This prevents the pin from accidentally becoming removed during rotation of the parts.

The following method is utilized for changing the set-up of the cambering mechanism. The rear end of the grinding wheel support 49 is elevated to take the weight off of the cam member. For this purpose a lifting bolt 73 having a hexagonal head 74 fitting into a hexagonal socket 75 in the end of lever 53 is passed through the frame 76 and provided with a nut 77 whereby rotation of the nut will effect axial movement of the bolt 73. A commercial form of ratchet wrench 78 is provided for rotating the nut 77.

When the weight of the grinding wheel support has been removed from the cam, the driving pin 70 is removed and the cam member 44 is pulled outward, disengaging the teeth 41 from the teeth 40 on the sleeve 39. The sleeve and cam are now free to be rotated. The same number on each scale of the cam and sleeve are now brought into register with the fixed zero mark 63 on the member 64. This operation properly positions the eccentrics relative to one another and it is only necessary to lock them in this position. This is accomplished by moving the cam member axially which effects re-engagement of the teeth 40 and 41, thereby connecting the sleeve positively to its actuator 38, and reinserting the driving pin 70 which positively connects the cam to the sleeve for joint rotation therewith. Attention is invited to the fact that the teeth 40 and 41 are made sufficiently small so that no rotation of the sleeve is necessary to effect interengagement of the teeth for any given setting thereof.

Since the cam is driven by the table it is necessary that the cam rotate in absolute synchronism with table movement, and means are therefore provided for removing all backlash in the drive from the table to the cam, and in such a way that the gear teeth always contact on the same side. This is accomplished by providing a hydraulic motor 79, as shown in Figure 3 and connecting the gear 80 of the motor through a pair of integral gears 81 and 82 to the gear 38.

By establishing a predetermined pressure in the hydraulic motor 79 a resistance may be created by the motor which must be overcome by the table drive motor 16, thereby taking out all the backlash when driving in one direction. In order to maintain the gear tooth contact as created by this condition, the motor 79 is made to serve as the dominant motor during travel in the other direction by increasing the pressure in the motor above that in motor 16.

It is, of course, obvious that should the requirement arise wherein the high point or low point of a camber is not in the longitudinal center of the work but located to one side or the other of the center, that the table should be positioned relative to the grinding wheel so as to position the high point or low point of the camber opposite the center of the grinding wheel before the cambering mechanism is set up.

10 There has thus been provided an improved form of cambering mechanism which may be more accurately set up than previous devices, and in which all the parts are positively driven, thus insuring a safer mechanism and one which may be very accurately reset for refinishing ground camber surfaces.

What is claimed is:

1. In a roll grinding machine having a power translatable work table and a pivoted grinding wheel support for moving a grinding wheel carried thereby toward and from the work table, the combination of means for tilting said support including a rotatable cam, a fixed stud, a sleeve having a portion eccentric with respect to the stud, for supporting the cam on the stud, a gear train driven by the table and including a final gear, concentric with the stud, means for adjustably interconnecting the sleeve with said gear for rotation thereby, means to connect the cam to the sleeve, said last-named means being removable to permit axial shifting of the cam member relative to the sleeve, and means operable by shifting of the cam member for disconnecting the driving connection between the final gear and said sleeve.

20 2. In a roll grinding machine having a roll grinding wheel support, the combination of means for tilting said support including a fixed stud, a sleeve eccentrically mounted on the stud, a circular cam eccentrically mounted on the sleeve, means to secure the cam and sleeve together in different relative rotated positions yielding different eccentricities of the cam with respect to the center of the stud including a series of graduation holes in one member, a series of vernier holes in the other member, a driving pin insertable in aligned holes, and power operable means positively connectible for rotating the sleeve.

30 3. In a roll grinding machine having a tilttable grinding wheel support, the combination of means for tilting said support including a fixed stud, a sleeve eccentrically mounted on the stud, a circular cam eccentrically mounted on the sleeve, means to secure the cam and sleeve together in different relative rotated positions yielding different eccentricities of the cam with respect to the center of the stud including a series of graduation holes in one member, a series of vernier holes in the other member, a driving pin insertable in the aligned holes, power operable means positively connectible for rotating the sleeve, and means associated with the cam sleeve and stud to indicate when a desired pair of holes corresponding to the desired eccentricity are in alignment.

40 4. In a roll grinding machine having a tilttable grinding wheel support, the combination of means for tilting said support including a supporting frame, a stud fixed in said frame, a sleeve eccentrically mounted on the stud, a circular cam eccentrically mounted on the sleeve, motion transmitting connections from the cam to said support, means to secure the cam and sleeve together in different relative rotated positions yielding different eccentricities of the cam with respect

to the center of the stud including a series of graduation holes in one member, a series of vernier holes in the other member, a driving pin insertable in aligned holes, detent means for holding the driving pin in driving relation and power operable means for rotating the sleeve.

5. In a roll grinding machine having a supporting frame and a grinding wheel support pivotally connected at one end to the frame, the combination of means for tilting said support including a fixed stud, a sleeve eccentrically mounted in the stud, a circular cam eccentrically mounted on the sleeve, a lever pivotally connected at one end to the frame and having the other end resting on the cam, said support resting on the lever midway of the length thereof, said cam and sleeve being relatively rotatable to yield different eccentricities of the cam, and means for actuating said lever to remove the weight of the support on the cam during said adjustment.

6. In a machine of the character described, means for effecting a controlled variable oscillation of a grinding wheel support, including a supporting stud, a drive train including a sleeve rotatably but non-translatably mounted on the stud, said sleeve having a concentric and an eccentric bearing portion, a drive train including a drive gear rotatably and translatable mounted on the concentric portion of the sleeve, a cam member rotatably and translatable mounted on the eccentric portion of the sleeve, interengageable means on the gear and sleeve effective in one position of relative translation of the parts to lock the gear and sleeve against relative rotation, and connections between the cam member and gear for effecting said interlocking engagement.

7. In a machine of the character described, means for effecting a controlled variable oscillation of a grinding wheel support, including a supporting stud, a drive train including a sleeve rotatably but non-translatably mounted on the stud, said sleeve having a concentric and an eccentric bearing portion, a drive train including a drive gear rotatably and translatable mounted on the concentric portion of the sleeve, a cam member rotatably and translatable mounted on the eccentric portion of the sleeve, interengageable means on the gear and sleeve effective in one position of relative translation of the parts to lock the gear and sleeve against relative rotation, connections between the cam member and gear for effecting said interlocking engagement, and means for locking the parts in engaged position.

8. In a machine of the character described, a wheel head oscillation controlling mechanism including a fixed stud, a sleeve rotatably mounted on the stud having a concentric and an eccentric bearing portion, a drive gear rotatably mounted on the concentric portion and an oscillation cam member rotatably mounted on the eccentric portion of the sleeve, means securing the sleeve for rotation on but against axial movement with respect to the stud, means rotatably coupling the cam member and gear elements for relative rotary and joint reciprocating movements, a multiple interlocking device carried by the gear and sleeve adapted for interengagement on translation of the gear in one direction to secure the gear and sleeve for joint rotation at any selected relative angular adjustment thereof, and additional means for securing the cam in rotatively adjusted position with respect to the sleeve.

9. In a machine of the character described, a wheel head oscillation controlling mechanism including a fixed stud, a sleeve rotatably mounted on the stud having a pair of exterior bearing portions, one of which is concentric with the stud and the other eccentrically disposed with respect thereto, a driving train including a gear rotatably mounted on the concentric portion of the sleeve and formed with a shifting spool, a cam member rotatably mounted on the eccentric bearing portion having a shifter interengaged with the spool of the gear, a first means retaining the cam member on the sleeve for limited axial movement with respect thereto whereby the cam may be translated to effect limited shifting of the gear axially with respect to the sleeve, and interengaging clutch means on the sleeve and gear in one direction for effecting driving engagement between the gear and sleeve.

10. In a machine of the character described, a wheel head oscillation controlling mechanism including a fixed stud, a sleeve rotatably mounted on the stud having a pair of exterior bearing portions, one of which is concentric with the stud and the other eccentrically disposed with respect thereto, a driving train including a gear rotatably mounted on the concentric portion of the sleeve and formed with a shifting spool, a cam member rotatably mounted on the eccentric bearing portion having a shifter interengaged with the spool of the gear, a first means retaining the cam member on the sleeve for limited axial movement with respect thereto whereby the cam may be translated to effect limited shifting of the gear axially with respect to the sleeve, interengaging clutch means on the sleeve and gear in one direction for effecting driving engagement between the gear and sleeve, and means for securing the cam member and gear against movement with respect to the sleeve.

11. In a machine of the character described, a wheel head oscillation controlling mechanism including a fixed stud, a sleeve rotatably mounted on the stud having a pair of exterior bearing portions, one of which is concentric with the stud and the other eccentrically disposed with respect thereto, a driving train including a gear rotatably mounted on the concentric portion of the sleeve and formed with a shifting spool, a cam member rotatably mounted on the eccentric bearing portion having a shifter interengaged with the spool of the gear, a first means retaining the cam member on the sleeve for limited axial movement with respect thereto whereby the cam may be translated to effect limited shifting of the gear axially with respect to the sleeve, interengaging clutch means on the sleeve and gear in one direction for effecting driving engagement between the gear and sleeve, the sleeve having a series of circumferentially arranged sockets formed therein, and a locking device carried by the cam member and selectively engageable in the sockets of the sleeve when said member is axially positioned to effect interclutching engagement between the gear and sleeve, whereby said member simultaneously secures the gear and sleeve against axial disengaging movement and the member and sleeve against relative rotary movement.
